(57) CLAIM

The ornamental design for a wind spinner, as shown and described.

DESCRIPTION

FIG. 1 is a perspective view of the wind spinner showing my new design.

FIG. 2 is a front view thereof;

FIG. 3 is a rear view thereof;

FIG. 4 is a side view thereof;

FIG. 5 is an opposite side view thereof;

FIG. 6 is a top view thereof;

FIG. 7 is a bottom view thereof; and,

FIG. 8 is a perspective view thereof showing the design of FIG. 1 in a position of use with blades thereon.

The broken lines in the drawings illustrate environmental subject matter that forms no part of the claimed design.

1 Claim, 3 Drawing Sheets
